REFRIGERATING APPARATUS

Harry B. Hull and Richard S. Gaugler, Dayton,
Ohio, assignors to General Motors Corporation,
Dayton, Ohio, a corporation of Delaware

Application November 30, 1934, Serial No. 755,382
Renewed August 5, 1936

2 Claims. (Cl. 62—103)

This invention relates to refrigeration.

It is an object of this invention to provide a refrigerator with an improved means for preventing dehydration of foods therein.

5 Further objects and advantages of the present invention will be apparent from the following description, reference being had to the accompanying drawing wherein a preferred form of the present invention is clearly shown.

10 In the drawing:

Fig. 1 is a view, partly in perspective and partly in cross-section, showing the form now preferred; and

15 Fig. 2 is a view of a slightly modified portion of Fig. 1.

In practicing this invention, a cabinet 100 is provided with a food storage compartment 101. A cooling unit is provided for maintaining proper temperatures in this compartment. This cooling unit may include an air cooling section 102 and an ice-making section 103. These sections may be formed of metal sheets properly welded together to form hollow passageways for the refrigerant.

20 25 Means for humidifying the air in the compartment 101 is provided, and this may take the form of a sump 104 placed in the bottom wall of the compartment 101. A purifier 105, which may be a cake of activated charcoal, is placed 30 in the sump 104. An air moistener is connected to this sump. Thus a water sprayer is connected with the sump 105, and takes the form of a rotating cone 106 dipping the water therein and being rotated by motor 109 energized from leads

35 40 45 Baffles 108 surround the cone 106 in such a manner that water sprayed by the cone impinges on the baffles 108 and prevents undue splashing of the contents of the food compartment 101. The air flowing in contact with the air cooling section 102 deposits moisture on this section which drips into a trough 111 and flows through the connection 112 into the sump 104. Any excess moisture overflows through the pipe 113 into an evaporator 114 placed outside of the compartment 101.

The evaporator 114 may take the form of a cup in which plates 114a are energized by electric current from the leads 110. When the water within the cup rises and submerges the plates 50 55 114a, current flows between the plates, heats the water and evaporates the same. When a sufficient amount of water has been evaporated the flow of current becomes so small or ceases and thus an automatic control of the evaporation of water is provided. The vapors created in the

drip water evaporator flow to the outside atmosphere through openings 114b.

A refrigerant liquefying unit 115 is provided. This may include a compressor 116, condenser 117, receiver 118 and motor 119 which drives the compressor 116. Liquid refrigerant flows from the unit 115 through the pipe 120 to an automatic expansion valve 121. From thence expanded refrigerant flows through the hollow spaces of the section 103 and from thence to the hollow spaces 10 15 of the section 102. The evaporated refrigerant returns to the unit 115 through the pipe 124.

Suitable trays 122 may be placed in the section 103. The hollow passageways in the section 102 may be made in the form of a zigzag passageway 15 as shown at 123.

An automatic control for the unit 115 is provided. This may take the form of a bulb 125 connected to a bellows 126 which actuates a snap switch 127 for the starting and stopping of the 20 motor 119.

25 In the operation of the device, the flow of refrigerant through the evaporator maintains the section 103 at a freezing temperature and the section 102 at a defrosting temperature such that no frost accumulates on the section 102, or, if frost does accumulate thereon, it melts with each idle period of the unit 115. The air in flowing over the evaporator is dehumidified by the condensation of moisture therefrom; but the air is rehumidified by the action of the sprayer 106 which thus restores moisture to the air. The purifier 105 maintains the water in proper condition.

30 35 40 45 In the modification shown in Fig. 2, the sump is provided with a slightly different sprayer which may take the form of a blower 130 driven by a motor 131. The blower 130 is connected to a nozzle 132 which is provided with a water pipe 133 connected to the sump. The suction action injects water into the air jet as it emerges at 132 as will be readily apparent. The intake for the fan 130 may be either from outside of the food compartment or from inside as is desired. The other portions of the apparatus shown in Fig. 2 50 55 may be substantially as shown in Fig. 1.

While the form of embodiment of the invention as herein disclosed, constitutes a preferred form, it is to be understood that other forms might be adopted, all coming within the scope of the claims 50 which follow.

What is claimed is as follows:

1. In combination, an enclosure having a unit therein which dehumidifies air within the enclosure, means for collecting water from said unit, 55

means for removing impurities from the collected water, and means including a rotatable cone in contact with the purified water for spraying same into air within the enclosure to rehumidify the air therein.

5 2. In combination, an enclosure having a unit therein which dehumidifies air within the enclosure, means for collecting water from said unit, means for removing impurities from the

collected water, means including a rotatable cone in contact with the purified water for spraying same into air within the enclosure to rehumidify the air therein, and means for evaporating excess water collected from said unit to atmosphere outside said enclosure.
